UNITED STATES PATENT OFFICE.

ALESSANDRO FORNER, OF NEW ROCHELLE, NEW YORK.

COMBINATION CIGAR-BOX.

1,120,469.

Specification of Letters Patent.

Patented Dec. 8, 1914.

Application filed July 5, 1912. Serial No. 707,784.

To all whom it may concern:

Be it known that I, ALESSANDRO FORNER, a citizen of the United States, residing at New Rochelle, in the county of Westchester and State of New York, have invented new and useful Improvements in Combination Cigar-Boxes, of which the following is a specification.

The general object of this invention is the provision of a combination cigar box which comprises a casing provided with means whereby a cigar may be cut after being extracted therefrom, said means being also adapted to release a match box which is normally held within the cover of said casing and which is adapted to be ejected therefrom whereby access may be had to the matches in said box, novel means being employed for retaining the latter in engagement with said cover.

In carrying out the objects of the invention generally stated above, it will be understood, of course, that the essential features thereof are susceptible to changes in details and structural arrangements, one preferred and practical embodiment being shown in the accompanying drawings, wherein:

Figure 1 is a perspective view of the cigar box constructed in accordance with the invention, the cover therefor being shown open. Fig. 2 is a vertical longitudinal sectional view therethrough. Fig. 3 is a vertical transverse sectional view. Fig. 4 is a detail perspective of the match box used in connection with the invention. Fig. 5 is a longitudinal section through the cover. Fig. 6 is a section through the box taken in line 6—6 of Fig. 5, the bottom of the box within 40 being broken away and the cover shown partly open. Fig. 7 is a similar section on line 7—7 of Fig. 5 with the cover shown closed.

Referring more particularly to the accompanying drawing in which like reference characters designate similar parts, it will be seen that the invention contemplates providing a casing 5 which is preferably constructed in the form of an ordinary cigar box, said casing being provided with a cover 6 which is hingedly connected thereto and which is provided with a recess 7. The cover 6 is provided with an auxiliary cover 8 which is adapted to be detachably connected to the cover 6 whereby the mechanism

in the latter which will be presently described is inclosed.

An elongated leaf spring 9 is adjustably secured to the inner surface of the rear side of the casing 5 by means of suitable fasteners 10 which are adapted to engage the elongated slots 11 formed in said spring. The spring 9 is made of resilient metal and the free end thereof extends above the top of the casing and is adapted to slide between the guide flanges 12 formed medially of the ends of the guide plate 13 which is secured transversely of the interior of the cover 6 by suitable fasteners 14. The guide plate 13 is provided intermediate the ends thereof with an opening 15 which is adapted to register with a similar opening 16 formed in the cover 6 whereby the end of a cigar may be inserted into the said openings and be cut by the beveled knife edge 17 of the spring 9 when the cover is raised.

The front of the casing 5 has secured thereto a plate 18 having an angular extension 19 provided with an elongated slot 20. Pivotedly connected to the plate 18 is a latch 21 having at one end a finger extension 22 which projects through the front of the casing 5 whereby the same may be depressed and release the pawl 23 which extends through the slot 20 and engages the slotted plate 24 carried by the auxiliary cover 8. A spring 25 is adapted to engage the finger extension 22 for normally retaining the latch 21 in engagement with the cover but upon pressure being exerted upon the said extension it will be seen that said latch will be released from engagement with the cover 6 and by reason of the resiliency of the spring 9, said cover will be caused to move to an open position. It will be seen by reference to Fig. 1 of the drawing that the openings 15 and 16 are uncovered when the cover is in an open position and upon the insertion of the end of the cigar into said openings and pressure being brought to bear upon said cover, the latter will be moved to a closing position and the spring 9 will slide between the flanges 12 and sever the end of the cigar.

A transverse strip 26 is also mounted in the recess 7 of the cover adjacent the guide plate 13 in parallel relation thereto and extending from said strip 26 at right angles thereto are the spaced guide strips 27 and 28 which are U-shaped in cross section. The

strip 27 is provided at one end thereof with an angular flange 29 which is adapted to engage the strip 26 whereby said strip 27 will be held in position. The guide strip 28 is 5 secured to the cover 6 in any suitable manner in parallel relation to the guide strip 27 and said strip is provided with a longitudinally extending slot 30 for a purpose which will be presently described. Slidably mounted 10 between the guide strips 27 and 28 is a receptacle 31 adapted to contain matches and said receptacle is provided in one side thereof with a laterally extending lug 32 which projects through the slot 30 whereby the 15 movement of the receptacle 31 is limited in the cover. When in the position shown in Fig. 1 of the drawing, the receptacle 31 is normally retained within said cover and said receptacle has secured to its inner end an angular catch 33 which extends laterally 20 from the said receptacle and which is provided adjacent its free end with a curved portion to form a notch 34 and contiguous to said notch there is provided a curved lip 35. The notch 34 is adapted to engage a pin 25 36 carried by the guide plate 13 when the match receptacle 31 is within the cover. When the cover is being closed, a tooth 37, which is carried by a reduced extension 38 30 formed upon the end of the spring 9, will come into contact with the lip 35 and thereby cause the notch 34 to disengage from the pin 36 thus releasing the receptacle 31. Said receptacle has secured thereto at its inner end 35 one end of an elastic band 39, the other end of said band being secured to the cover 6 in any suitable manner. It will thus be seen that upon the release of the receptacle 31 said band will cause said receptacle to move 40 outwardly through an opening 40 formed in the end of the cover 6 and the outward movement of said receptacle is limited by the contact of the lug 32 with the end of the slot 30 in the guide strip 28, thus rendering the contents of said receptacle accessible. The catch 45 33 is returned to its normal position by means of a coil spring 41 one end of which is secured to the catch 30 while the other

end is secured to said receptacle. After the cover has been closed, the same is retained in 50 its position by the latch 21 which engages the plate 24 carried by the auxiliary cover 8. After a match or matches have been removed from the receptacle 31 the same may be pushed inwardly until the notch 34 again 55 engages the pin 36 and the said receptacle is held within the cover until again released in a manner which has been previously described.

From the foregoing description taken in 60 connection with the accompanying drawing, it will be seen that the invention contemplates providing a combination cigar box which is comparatively simple in construction thus reducing the cost of manufacture 65 of the same to a minimum and which is durable and effective in carrying out the purpose for which it is designed.

What is claimed is:—

1. A box including a hollow cover formed 70 with an opening to receive a cigar tip, a match receptacle slidably mounted therein, means for projecting the receptacle beyond the wall of the cover, means for locking the receptacle against action of such projecting 75 means, a spring co-operating with the cover to elevate the same and formed with a cutting edge to sever the cigar tip inserted in said opening in the cover, said spring having a projection to release the locking means 80 in the closing movement of the cover.

2. A box including a hollow cover, a receptacle slidably mounted in the cover, means for projecting the receptacle beyond the wall of the cover, means for locking the 85 receptacle against the action of such projecting means, and means for elevating said cover and operating in the closing movement of the cover to releasably actuate said locking means. 90

In testimony whereof I affix my signature in presence of two witnesses.

ALESSANDRO FORNER.
